UNITED STATES PATENT OFFICE.

REID T. STEWART, OF PITTSBURGH, PENNSYLVANIA.

FUEL-SUPPLY SYSTEM FOR INTERNAL-COMBUSTION ENGINES.

1,313,925.

Specification of Letters Patent. Patented Aug. 26, 1919.

Continuation in part of application Serial No. 72,384, filed January 17, 1916. This application filed May 29, 1918. Serial No. 100,436.

To all whom it may concern:

Be it known that I, REID T. STEWART, a citizen of the United States, residing at Pittsburgh, in the county of Allegheny and 5 State of Pennsylvania, have invented a new and useful Improvement in Fuel-Supply Systems for Internal-Combustion Engines, of which the following is a full, clear, and exact description, reference being had to 10 the accompanying drawings, forming part of this specification, in which—

Figure 1 is a sectional elevation illustrating one form of my invention;

Fig. 2 is a similar view largely diagrammatic showing another form;

Figs. 3, 4, 5 and 6 are fragmentary detail views showing different ways of giving one of the valves a lead over the other one;

Fig. 7 is a view similar to Fig. 2, showing another modification; and

Fig. 8 is a sectional elevation illustrating still another form of my invention.

My invention has relation to fuel supply systems for internal combustion engines, 25 and more particularly to a system of this character which is designed for use when the main source of fuel supply is either permanently or temporarily located at a lower level than the carburetor, and in which 30 the suction of the engine is utilized to cause a flow of the fuel from the main source of supply to the carburetor.

One object of my invention is to provide a system of this character which shall be 35 simple and efficient in its construction and mode of operation under varying service conditions.

Another object is to provide a vacuum fuel feed system, in which the vacuum is 40 continuous in its action and in which the vacuum range may be made less to any desired extent than that in the engine manifold.

A further object is to provide a fuel feed 45 system of this character which shall have no atmospheric vents at any point between the main fuel supply tank and the engine intake.

A further object of the invention is to 50 provide means whereby the fuel feed may be operated practically continuously with a small degree of vacuum, with open throttle, and therefore, with high volumetric engine efficiency, thereby giving the maximum

power when power is most demanded, while at the same time, sufficient vacuum may be 55 had with a partially closed throttle for lifting the fuel to the top of a supplemental supply tank.

Another object of my invention is to provide means of novel and efficient character 60 for controlling the fuel delivery from the supplemental tank to the float chamber of the carburetor.

A still further object is to provide apparatus of this kind, in which the parts are 65 few and simple in character and can be readily assembled and which are readily accessible for renewal or repairs.

Referring first to that form of my invention shown in Fig. 1, the numeral 1 designates a supplemental tank which is supplied with liquid fuel by means of an unrestricted passage 2, connecting its upper portion with a main fuel supply tank 3. A partial vacuum is maintained in the supplemental 70 tank by means of a restricted passage 4, which connects its upper portion with the upper portion of the float chamber 5 and which acts also as a fuel passage, as will be described. The float chamber 5, communicates by means of a passage 6 with the carbureting chamber 7, wherein partial vacuum exists. In the form shown in this figure, I have shown the pipe or tube forming the 75 passage 4 as extending upwardly through the supplemental tank, which is shown as supported directly upon the float chamber. 8 designates another fuel feed passage leading from the bottom of the supplemental tank into the upper portion of the float 80 chamber. The passages 4 and 8 are controlled, respectively, by valves 10 and 12, whose stems 11 and 13 rest upon the top of a float 14, preferably at diametrically opposite points and equidistant from the axis 95 through the center of flotation. The weight of the valve 10 and its stem 11 is made greater than that of the valve 12 and its stem 13, (or the left side of the float may be over-weighted in any other suitable manner) 100 thereby giving a tendency to the float to list toward the side which carries the heavier load, and in order that the valve 10 may always open before the valve 12. The float is preferably mounted on a vertical tapered 105 pin 15, the float having a central opening

engaging said pin in a manner to permit of the free vertical movement of the float, combined with a limited oscillating or tipping movement. The extent of the actual tipping movement of the float, due to the excess weight on the side of the valve 10, is preferably limited by the amount of taper to be given to the pin 15, or it may be to the walls of the opening 16. This taper is made sufficient to cause the valve 12 to open the instant that sufficient fuel ceases to enter past the valve 10.

The passage 4, which connects the top of the supplemental tank 1 with the upper portion 15 of the float chamber, acts as a main fuel feed passage, as a suction or vacuum passage, and also as an air fuel vapor vent. This passage, controlled in the manner described, functions to maintain a store of fuel in the 20 supplemental tank up to the level shown in Fig. 1, whenever the vacuum produced by the engine is sufficient to lift the fuel to the top of the supplemental tank. Any condition which causes an interruption of 25 fuel flow to the float chamber 5, by way of the main fuel passage 4, will automatically put into action the supplemental fuel passage 8, whereby the fuel will be drawn from the supply stored in the supplemental tank 30 until such time as the passage 4 resumes its normal operation.

The air inlet 18 of the carbureting chamber 7 is controlled by a valve 17. This valve is held to its seat 19 primarily by 35 means of the spring 20, and secondarily by means of a piston 21, attached thereto and slidably mounted within the cylinder 22, which is supported within or adjacent to the air inlet 18. The upper end of the cylinder 40 22 is closed, and the space within communicates by means of a passage 23 with the carbureter outlet 24 on the engine side of the throttle valve 25. When the throttle valve is wide open, as indicated in the dotted position 25^a, the vacuum in cylinder 22 is substantially equal to that in the carbureting chamber 7, and for this condition the pressure of valve 17 against its seat is due to the action of the spring 20 alone. When, however, the throttle valve is partially closed, as indicated in full lines in Fig. 1, the degree of vacuum is greater in the cylinder 22 than it is in the carbureting chamber 7. This causes the piston 21 to exert an upward pull 50 on the air valve 17. This upward pull, which is substantially zero with a wide open throttle, may be increased to any desired extent for partially closed throttle, by suitably enlarging the diameter of the piston 21, with respect to the air valve 17. This construction and arrangement makes it possible to operate a continuous vacuum fuel feed system on a small degree of vacuum with open throttle, and therefore, with high volumetric engine efficiency. This condition

gives maximum power at times when power is most demanded, while at the same time, with the throttle partially closed, sufficient vacuum may be had for lifting the fuel to the top of the supplemental tank.

The air valve 17 and its seat 19 are preferably given such shape as to form an annular Venturi passage for the inflow of air to the carbureting chamber 7. The fuel inlet 26 is preferably located at the throat 70 of this venturi. The fuel is preferably drawn up through the hollow valve stem 27, and is distributed to the periphery of the valve 17 by means of the passage or passages 28, formed within the air valve itself and 75 leading to the outlet 26. This outlet 26 preferably consists of a narrow slot extending around the periphery of the valve, the latter being formed in two sections, as shown, to provide for this slot, which is 80 located at the point of contact of the valve with said seat. I prefer to give the distributing passage 28 and the fuel outlet opening 26 the inclined or conical form 85 shown for the purpose of causing the fuel to issue more or less in the direction taken by the air while passing through the throat of the venturi. By thus adding an induction action to the venturi action, I obtain a more effective flow of fuel from the float 90 chamber to the carbureting chamber. By the combined action of the air valve 17, the fuel outlet 26, the vacuum piston 21, the passage 23, and the throttle 25, I am enabled to produce a perfect admixture of the fuel 95 with the air when such condition is desired viz., when operating under partially closed throttle, especially when using liquid fuels which vaporize with difficulty.

The lower end of the hollow valve stem 27 100 has secured thereto a piston 29, working in the liquid dash pot 29^a, which may be supplied from the float chamber by means of openings 29^b in the piston. The purpose of this dash pot is to prevent any tendency 105 of the valve 17 to vibrate or flutter. The piston 29 has a depending hollow hub or sleeve which telescopes over a metering pin 30, and which terminates in the annular seat 32. This pin is of gradually reduced diameter 110 toward its lower end, its upper end being made of such size as to easily enter from below through the seat 32; and said pin is of sufficient weight to seat firmly upon an adjusting screw 35. The weighted lower 115 end 31 has therein a cone-shaped cavity 33, which engages the conical point 34 of the adjusting screw 35. This construction provides in a simple manner for the longitudinal adjustment of the metering pin and also a perfect means of lateral self-adjustment of the pin to its surrounding seat 32. The construction and arrangement also permits of the parts being readily assembled and easily accessible for any desired purpose. The 120

125 130

lower section 29^c of the dash pot 29^a is made removable for this purpose.

In the form of my invention shown in Fig. 2, the parts are generally constructed and arranged substantially as in Fig. 1, and corresponding parts have been given the same reference numerals with the letter "a" affixed thereto. In this form, however, instead of a single float 14, controlling the two valves, separate floats 36 and 37 are employed. The float 37 is set at a higher level than the float 36, so that the valve 10^a will open sooner than the valve 12^a. By immersing the float 37 to a less degree than the float 36, the valve 10^a may be given any desired lead of opening over the valve 12^a. In this figure, I have also shown the carbureter as having an anterior throttle valve A, and a posterior throttle valve B, the two throttles having an adjustable connection C, by which they may operate in unison.

In the form shown in Fig. 3, I employ a single float 38, and the proper lead is given to the valve controlling the primary feed passage 4^b, by immersing one end of the float deeper than the other, this more deeply immersed end actuating the valve 12^b, and its other end actuating the stem 11^b of the main feed valve. In this case, the stem 11^b is pivotally connected to the float.

In Fig. 4, the same result is obtained by seating the valve stem 13^c upon a spring 39 of the single float 40, upon which the valve stem 11^c rests. In this construction, the valve 12^c will first seat, but the spring 39 will yield to the further upward movement of the float until the other valve is closed.

In Fig. 5, I show still another way of accomplishing the same result by the use of a divided float having the superimposed sections 41 and 42. The upper part 41 controls the stem 11^d of the main valve, while the lower part 42 carries and controls the supplemental valve 12^d. As long as the fuel in the float chamber does not rise above a certain level, the two float parts act as a unit, but as the depth of the fuel increases and the valve 12^d closes, the upper float member will continue to rise and close the other valve.

Another way of accomplishing the same result is shown in Fig. 6, in which the single float 43 acts at one side of the center of the lever arm 44, the valve 11^e being carried on the longer arm of this lever and the valve 12^e on the shorter arm thereof.

Still another arrangement for the same purpose is shown in Fig. 7, in which a single float 45 of ball form is employed, the stem 13^f of the valve 12^f being pivoted to one side of the float, and the stem 11^f of the valve 10^f being pivoted to the opposite side of the float. Valve 10^f having its stem 11^f heavier than the valve 12^f, and its stem 13^f, the result is a tendency to tip the float so as to first close the valve 12^f.

This tipping tendency is limited by the stop 46.

In this figure, I have also shown an arrangement of the air inlet valve for the same purpose as that shown in Fig. 1, but somewhat differently applied. 47 designates the air inlet, 48 the controlling valve therefor, 49 the piston connected to the stem of said valve and working in the cylinder 50, whose upper end is connected by a passage 51 with the outlet passage 52, leading to the engine. The passage 51 communicates with the passage 52 at the engine side of the throttle valve 53. The action of the piston 49 and cylinder 50 is similar to that of the piston 21 and cylinder 22, first described. The top of the float chamber 5^f is connected by means of passage 6^f, shown in dotted lines, to the space adjacent to the inlet controlled by valve 48. The construction shown in Fig. 7 is, however, one which can be readily applied to various forms of carbureters. In this figure, the pipe 2^f from the main storage tank connects with the pipe 4^f in which the valve stem 11^f is located, with a branch 90 connection 54 leading into the supplemental tank. In this arrangement, the main feed is directly from the main storage tank, surplus fuel passing through 54 into the supplemental tank.

In Fig. 8, I have shown still another embodiment of my invention, generally similar to that shown in Fig. 1, but involving a number of modifications. Parts of this figure which correspond to similar parts in Fig. 1 are given the same reference numerals with the letter "g" affixed. It will be noted that in Fig. 8, the valve 17^g is reversed with respect to the valve 17 of Fig. 1, and is arranged to seat downwardly by gravity instead of upwardly by the action of a spring. The action of the piston 21^g is reversed also, the suction passage 28^g communicating with the cylinder 22^g, below the said piston. In this figure, the feed passage for the fuel instead of being within the stem of the valve, as in Fig. 1, is formed by a separate passage 56 in the wall of the carbureter, and communicates with an annular passage 57 below the seat for the valve 17^g, and communicates with the seating surface by an annular discharge slot 58. The fuel is thus discharged at a similar point to that of Fig. 1, but independently of the valve. The metering pin 30^g is carried by the dash pot piston 29^g and adjustment thereof is obtained by providing the stem 27^g of the valve with a slotted head 59. The lower end of the valve stem has a threaded connection at 61 with the piston 29^g. The correct adjustment is secured by means of a pawl or detent 62, engaging the toothed wheel 63 in the lower end of the valve stem. By removing the cap 60, the stem 27^g can be turned by means of a screw driver, thus 130

raising or lowering the piston and correspondingly adjusting the metering pin.

In this figure I have also shown a modified arrangement of the float 14^g, in which 5 the centering pin 15 of Fig. 1 is omitted and substantially the same result is obtained by making the float of downwardly tapered or frusto-conical form. The side of the float upon which the valve stem 11^g rests is 10 overweighted with respect to the opposite side either by the increased weight of said stem or in any other suitable manner.

It will be readily understood that the 15 double valve arrangement herein shown and described effectively provides for the proper supply of fuel to the float chamber under all conditions. So long as the vacuum action produced by the engine is sufficient to maintain the supplemental tank filled to 20 about the level shown, the supply to the float chamber is past the main valve. When, for any reason, the level of fuel in the supplemental tank falls, the supplemental valve then opens and the fuel stored in such tank 25 is utilized.

The main valve automatically prevents fuel-flooding under any operating condition. At the same time, the main valve automatically provides, when required, free communication between the upper portions of 30 the supplemental tank and the float chamber for the purpose of venting and of transfer of suction.

It will be noted from Fig. 7 that the supplemental tank need not be supported directly upon the float chamber, but that it may be placed in any convenient relation thereto and that the connections between this tank and the float chamber may be vari- 40 ously arranged.

My invention is susceptible of various other modifications within the spirit and scope of the appended claims.

The present application is, in part, a continuation of my copending application, Serial No. 72,384, filed January 17, 1916.

I claim:

1. In a fuel supply system for internal combustion engines, a main supply tank, a 50 supplemental tank, a carbureter having a float chamber supplied from the supplemental tank, float means in the float chamber, a valve actuated by said float means and controlling the supplemental fuel supply from the supplemental tank, there being suction passages connecting the upper portion of the float chamber with the upper portion of the supplemental tank and with the carbureting chamber of the carbureter, 55 one of said suction passages also forming the main fuel supply passage from the supplemental tank to the float chamber, and a valve controlling the main fuel supply passage and controlled by said float means, sub- 60 stantially as described.

2. In a fuel supply system for internal combustion engines, a main supply tank, a supplemental tank, a carbureter having a float chamber supplied from the supplemental tank, float means in the float chamber, a valve actuated by said float means and controlling the supplemental fuel supply from the supplemental tank, there being suction passages connecting the upper portion of the float chamber with the upper portion 75 of the supplemental tank and with the carbureting chamber of the carbureter, one of said suction passages also forming the main fuel supply passage from the supplemental tank to the float chamber, and a valve controlling the main fuel supply passage and controlled by said float means, said last named valve having means for giving it a lead of opening over the supplemental fuel control valve, substantially as described. 85

3. A carbureter having a float chamber, float means in said float chamber, a storage chamber, a feed connection leading from the lower portion of the storage chamber into the float chamber, another feed connection 90 leading from the upper portion of the storage chamber into the float chamber, a valve controlled by said float means for each of said connections, and means whereby the valve for the last named connection may be 95 given a lead of opening over the valve for the first named connection, substantially as described.

4. In a fuel supply system for internal combustion engines, a main supply tank, a 100 supplemental tank having a supply connection with the main tank, a carbureter having a float chamber supplied from the supplemental tank, a float means in said float chamber, a valve actuated by said float means 105 and controlling the supplemental fuel supply from the supplemental tank, there being suction passages connecting the upper portion of the float chamber with the upper portion of the supplemental tank and with the carbureting chamber of the carbureter, one of said suction passages also forming the main fuel supply passage from the supplemental tank to the float chamber, and another valve controlling the main fuel 110 supply, said last named valve having means for giving it a lead of opening over the supplemental fuel control valve, substantially as described. 115

5. In a fuel supply system for internal 120 combustion engines, a supplemental tank, means operated by the engine for supplying the supplemental tank with fuel, another chamber at a lower level than the supplemental tank, a fuel supply passage leading 125 from the upper portion of the supplemental tank into the last named chamber, another fuel supply passage leading from the lower portion of the supplemental tank into the last named chamber, a valve for each of 130

said connections, and means for giving one of said valves a lead of action over the other valve, substantially as described.

6. In a fuel supply system for internal combustion engines, the combination with a fuel storage tank, of a chamber located at a lower level than said tank and having two feed passages connecting it with different levels of said tank, a separate valve controlling each of said passages, and means for giving one of said valves a lead of action over the other, substantially as described.

7. In a fuel supply system for internal combustion engines, the combination of a fuel storage tank, a float chamber located at a lower level than said tank and having two feed passages connecting it with different levels of said tank, a separate valve controlling each of said passages, and a tipping float for actuating said valves, said float acting to give one valve a lead of action over the other, together with means for tipping the float, substantially as described.

8. In a fuel supply system for internal combustion engines, the combination with a fuel storage tank, of a float chamber located at a lower level than said tank and having two feed passages connecting it with different levels of said tank, a separate valve controlling each of said passages, and means for giving one of said valves a lead of action over the other, said means comprising a tipping float which supports the valves, and one of said valves being weighted in excess of the other, substantially as described.

9. In a fuel supply system for internal combustion engines, the combination with a main fuel storage tank, of a supplemental fuel storage tank, a chamber having a feed connection with said supplemental storage tank, and a suction passage leading from the engine to the main storage tank and communicating with the supplemental storage tank above the level of fuel therein, said passage communicating with said chamber and also forming a fuel supply connection for said chamber, substantially as described.

10. In a fuel supply system for internal combustion engines, the combination with a main fuel storage tank, of a supplemental fuel storage tank, a chamber having a feed connection with said supplemental storage tank, and a suction passage leading from

the engine to the main storage tank and communicating with the supplemental storage tank, said passage communicating with said chamber and also forming a fuel supply connection for said chamber, together with separate valves controlling the two fuel supplies for said chamber, and means for giving one of said valves a lead of action over the other one, substantially as described.

11. In a fuel supply system for internal combustion engines, a chamber, a main storage tank, a supplemental storage tank, means whereby the action of the engine is caused to raise the fuel from the main storage tank, the float chamber having two separate fuel feed connections, separate valves for controlling said connections, and means operated by the level of the fuel in said chamber for controlling said valves and for giving one of said valves a lead of action over the other, substantially as described.

12. In a fuel supply system for internal combustion engines, the combination with a fuel storage tank, of a float chamber located at a lower level than said tank and having two feed passages connecting it with different levels of said tank, a separate valve controlling each of said passages, and means for giving one of said valves a lead of action over the other, said means comprising a tipping float which supports the valves, one side of the float being weighted in excess of the other, substantially as described.

13. In combination, a carburetor having a fuel feeding nozzle, a chamber feeding said nozzle, a supplemental chamber feeding said first-named chamber, a storage tank feeding said supplemental chamber, said supplemental chamber normally holding a reserve supply of fuel and feeding said first named chamber by means of an excess over said reserve supply, and means controlled by the level of fuel in said first named chamber for drawing on said reserve supply when the main supply fails to maintain the fuel level in said first named chamber between predetermined limits.

In testimony whereof, I have hereunto set my hand.

REID T. STEWART.
